LUBRICATING MECHANISM FOR DEEP WELL DRILLS

Filed Aug. 19, 1922

UNITED STATES PATENT OFFICE

FRANK L. O. WADSWORTH, OF PITTSBURGH, PENNSYLVANIA

LUBRICATING MECHANISM FOR DEEP WELL DRILLS

Application filed August 19, 1922. Serial No. 582,860.

My invention relates to lubricating mechanism of the generic character described in my copending application Ser. No. 582046 filed August 15th, 1922, and the present application is, in part, a continuation of this earlier one. The general object of the improvements herein set forth is the provision of a simple and reliable lubricating mechanism for deep well boring tools or other apparatus which must be operated at great distances below the surface of the ground, or at other inaccessible points; and one of the main features of this improved mechanism is the utilization of the weight of the drill stem, or driving shaft, to effect the forced flow of the lubricant from a suitable working chamber, to all of the bearing or wearing surfaces of the tool or other apparatus when the latter is in operation.

A more specific purpose of the present improvements is the provision of an auxiliary or reserve reservoir of lubricant which is not subjected to the weight of the drill stem parts; and the provision of means whereby successive amounts of lubricating material may be transferred from the said reserve reservoir to the working chamber—without interrupting the normal operative movements of the drill head parts—and then forced from said working chamber to the desired points under a controllable and predetermined pressure component of the total drill stem weight.

A further object of these improvements is to provide a combination of elastic and hydraulic pressure forces for balancing and counteracting the major portion of the drill stem or driving shaft weight; and to provide means for readily varying the magnitude of these balancing forces, as this weight increases or diminishes, so as to obtain a pre-adjusted residual gravity pressure for effecting the forced discharge of lubricating material from the working chamber.

Another object of my present invention is the provision of an improved form of drill stem whose working weight—when immersed in a drill hole that is filled with water or other flushing liquid—will be substantially less than that of an ordinary tubular drill stem of

the same power transmitting capacity;—thereby reducing the necessary “balancing” forces for supporting or counteracting the major portion of the drill stem pressure on the lubricant in the working chamber, and also sensibly diminishing the strain on the suspension cables when the drill stem assembly is being lifted from, or lowered into, the bore hole.

Still another purpose of that part of my invention which has to do with the provision of an improved drill stem, is the provision of a double-walled-two-conduit driving shaft member which can be used to carry a stream of flushing liquid to the bottom of the bore hole, and also concurrently, or independently, used to convey either lubricant, or compressed air, or other fluid, from the surface of the ground to chambers in the drill head;—thereby permitting, in some cases, of longer continued or more effective operations than are possible with deep well apparatus of the usual construction.

Other objects and advantages, and additional features, of my present improvements will be made apparent, to those skilled in the art, by the following more detailed description of certain illustrative embodiments thereof, which are shown in the accompanying drawings, in which:

Fig. 1 is a side elevation of a portion of a drill head and drill stem construction which exemplifies this invention; Fig. 2 is an enlarged longitudinal section, on the plane 2—2 of Fig. 1, of the lower part of the first figure; Fig. 3 is a cross section on the plane 3—3 of Fig. 2; Fig. 4 is a longitudinal section on the same plane as Fig. 2, of the upper part of Fig. 1; and Fig. 5 is a sectional view, similar to that of Fig. 2, which illustrates a second embodiment of my improvements.

The construction shown in Figs. 1, 2 and 3 comprises a drill head 4 which is provided with a hollow driving sleeve extension 6, and a plunger member 8 that is attached, at its upper end, to the lower extremity of a drill stem 11 by means of the perforated cap 9. The upper portion of the sleeve extension 6 is provided with three longitudinal grooves or keyways 5, 5, 5; and the lower part of the plunger

8 is provided with three correspondingly spaced slots; and the two members are held in relatively reciprocable, but non-rotatable, relation by three keys, 7, that are fitted tightly 5 into the said slots and slide freely in the said grooves. The upper end of the sleeve 6 is threaded to receive a ring 10 that serves the joint purpose of closing the upper ends of the keyways 5—thereby limiting the longitudinal 10 separation of the members 6 and 8—and of supporting a suitable packing ring and gland for the slidably engaged members. The head 4 is also provided with a tubular extension 12 which communicates at its lower 15 end with an opening 13 that leads to the cutters on the said head, and which is engaged at its upper extremity, by a bearing 14 in the hollow screw sleeve 15. This sleeve is rotatably connected to the plunger cap 9 by means 20 of the tube 17 and the shouldered collar 18; and its threaded periphery is engaged by a piston 16 that fits closely in the plunger member 8. A powerful coil spring 19, which is capable of supporting a substantial part of the 25 drill stem weight, is interposed between the adjustable piston 16 and a plate 20 that rests on the upper face of the drill head 4. A second coil spring 21 is also interposed between the packing ring gland for the bearing 14 and 30 a similar packing gland 22 for the central opening in the plate 20.

The annular space between the sleeve and plunger, 6 and 8, and the tube 12—which is closed at the top by the sleeve and piston 35 15—16 and at the bottom by the plate 20—constitutes a lubricant chamber, which is in communication with the space above the piston 16 through a spring closed valve 25, and with the space below the plate 20 through a port 26 40 that is controlled by the “packless” compressed air valve 27. The flexible metal bellows or “sylphon” of this fluid pressure control valve is connected with a lateral opening that contains an ordinary Schrader tire valve 45 28 through which the said bellows can be charged to any desired pressure. The annular space 29 between the recessed lower face of the plate 20 and the top of the drill head 4 is in communication with the bearings of the drill 50 head cutter bits through a duct or ducts 23.

In the use of this apparatus the position of the piston 16 is adjusted—by applying a suitable wrench to the octagon headed collar 18—until the initial tension of the coil 55 spring 19 is sufficient to support a very substantial part of the weight of the drill stem at the desired depth of operation. The upper and lower chambers—on the two sides of this piston 16—are then filled with lubricant 60 through the openings 24 in the plunger cap 9 (preferably by inverting the tool and pumping in the material through a suitable connection that is attached to the end of the cap); and the lower drill stem section 65 is next inserted and screwed down until

it meets the end of the collar 18 and seals off the openings 24 from the central passage of the tube 17. The air pressure in the bellows of the control valve 27 is then adjusted until it is just insufficient to keep the port 26 closed against the action of the residual or unbalanced gravity pressure on the parts, 8—15, 16, when the full operating length of drill stem is in place and the drill head has been lowered into contact with the bottom of the bore hole. Under such circumstances the weight of the drill stem-plunger assembly 11—9—8—15—16—17 etc. will be supported in part on the elastic members 19 and 21 and in part by the aggregate or accumulated hydraulic pressure on the lower exposed faces of the parts 8—15 and 16;—this latter force being equal to the area of the said faces multiplied by the unit surface pressure on the head of the valve 27. Since this head 70 is very small as compared with the total end area of the parts 8—15 and 16; and since it is also considerably smaller than the spring bellows on which it is mounted; it will require only a relatively small air pressure in the said bellows to resist a gravity pressure of several thousand pounds on the plunger heads; and it would be possible to sufficiently restrain the downward movement of the said heads relatively to the driving sleeve 6—and 75 correspondingly control the discharge of lubricant through the passages 26 and 23—by the use of the fluid pressure valve 27 alone. But I prefer to employ the coil springs 19 and 21, as supplemental or complementary to the air spring control element 27, because the supporting tension of the aforesaid coil springs increases as the drilling operation 80 proceeds and the members 6 and 8 gradually approach each other—thereby effecting a closure of the valve 27 against the diminished unbalanced weight of the drill stem before the key 7 engage with the lower ends of the grooves 5—and also because of the action of these springs in immediately restoring the 85 said members to their initial-fully separated position when the drill stem is lifted a slight distance. This expansion movement of the partially emptied lubricant reservoir causes the valve 25 to open and admit a fresh supply of unguent from the upper reserve chamber; and when the drill stem is again lowered the residual gravity pressure that remains unbalanced by the expanded springs 19 and 21 90 overcomes the hydraulic resistance to the flow of liquid through the air spring valve 27 and reestablishes the temporarily interrupted flow of the lubricant to the cutter bearings. With this construction it is, therefore, possible to continue the drilling operations—with an occasional momentary lifting of the drill stem parts—until the large supply of lubricant above the piston 16 has been 95 exhausted; and this long continued opera- 100

tion involves only a small reciprocatory or sliding movement of the plunger 8 relatively to the drill sleeve 6.

Fig. 5 illustrates a modification of the plunger head construction shown in the lower part of Fig. 2. In this second exemplification of my improvements the driving sleeve 6^a is detachably secured to the drill head 4 and is provided with three short keyways 5^a; and the plunger tube 8^a is internally threaded at its lower end to engage an inverted cup shaped head 16^a. The enlarged rim of this cup, and the adjacent portion of the plunger member 8^a, are in close sliding engagement with the interior of the sleeve 6^a; and are held in non-rotatable relation thereto by the inset keys 7^a which are clamped in their seats on the member 16^a by the end of the tube 8^a and which move longitudinally 20 in the keyways 5^a. The inner surface of the cup shaped head is accurately ground to make a very close slip-joint with the exterior of the upright cup piston 20^a which is supported on the upper face of the drill head 4; and the engaging surfaces of the parts 16^a and 20^a are provided with both a series of fluid packing grooves and with flexible cup washers in order to secure and maintain a fluid tight contact between them. A central tube 12^a is screwed into the top of the drill head and extends upward, through a fluid tight packing 14^a in the head 16^a, into the lower end of a tube 17^a which leads to an upper perforated cap—similar to that indicated at 9, Figs. 1 and 2—on the top of the plunger 8^a. A powerful coil spring 19^a is interposed between the reversely turned cup members, 16^a—20^a, and a second spring 21^a—of considerably less strength—is interposed between the member 20^a and the movable gland of the packed bearing 14^a. The air tight chamber containing these springs is in communication—through an annular space between the base of the piston 20^a and the tube 45 12^a—with a duct 28^a that contains a Schrader tire valve 28^b which is sealed into one side of the drill head 4. The annular chambers above and below the head 16^a communicate with each other through a longitudinal 50 passageway 25 that is normally closed at the top by the downwardly opening flap valve 25^b; and the lower chamber is provided with a spring closed valve port 26^a—27^a that opens into an annular chamber 29^a from 55 which suitable ducts, 23, lead to the drill head cutter bearings.

The necessary operative balance between the weight of the drill-stem-plunger assembly and the conjoint spring and hydraulic pressure supports for the plunger head 16^a of this last described construction is obtained as follows: The tension of the spring support for the ball valve 27^a is first roughly adjusted, by screwing down the upper seat of that valve, until the latter is held

closed against a reservoir pressure of from 25 to 200, or more, pounds per square inch (according to the depth of operation and the diameter of the drill head etc.); and compressed air is then introduced into the spring chamber—through the valve 28^b—until the combined supporting effect of the initially tensioned coils 19^a—21^a and of the confined air is not quite sufficient to balance the hydraulically uncompensated component of the 70 drill stem weights when the drill head is in operative position at the bottom of the bore hole. Under such circumstances the valve 27^a will be held open by the small unsupported component of the gravity pressure on 80 the lubricant below the plunger head 16^a; and the latter will be slowly fed to the cutter bearings until the approach of the members 4 and 8^a (i. e., 20^a and 16^a) has increased the tension, and the resultant supporting effect, of the spring elements to a point where the gravity pressure on the plunger head 16^a is overbalanced. The flow of lubricant to the ducts 23 will then be arrested by the closure of the valve 27^a; but in order to reestablish 85 this flow it is only necessary to momentarily lift the drill stem—without stopping the rotative movement of the tool—and thereby permit a fresh supply of material to pass from the upper storage reservoir, through the downwardly opened valve 25^b, to the expanding chamber below the head 16^a. When the drill stem is again lowered, the gravity pressure on the new charge of lubricant is sufficient to overbalance the supporting tensions of the expanded air-reinforced-springs 90 19^a and 21^a and of the hydraulic accumulator action of the spring valve elements 26^a—27^a, and the latter valve will be reopened to admit more lubricant to the distribution chamber and ducts 29^a—23.

As has already been indicated the joint and complementary actions of the coil springs 19 and 21 (or of the air-reinforced-springs 19^a—21^a) and of the spring pressed valve 27 (or 27^a), are capable of balancing a gravity pressure of many thousand pounds on the plunger assembly; and the tension of these springs can be adjusted over an extended range to compensate or counteract the major 110 portion of the widely varying weight of the drill stem parts for both shallow and deep bore holes. But when the drilling operations are carried on at a depth of several thousand feet, the total weight of the drill stem member amounts to many tons; and it is desirable 115 to effect a substantial reduction in that weight, not only for the purpose of diminishing the size of the springs 19 and 21 (or 19^a—21^a) and the closing pressure on the spring 27 (or 27^a), but for many other reasons. Another feature of my present invention is directed to this reduction in weight, which is accomplished by the use of the "semi-floating" drill stem structure that is shown 120 125 130

in Figs. 1 and 4. This structure comprises two concentric pipes 30 and 31 of substantially different diameters, each of which preferably consists of uniform lengths of cold drawn tubing that are integrally connected at their ends by special male and female couplings 32 and 33. Each male coupling 32 is provided with an outer threaded portion that engages one end of an outer tube length 31 and an inner threaded portion that engages the adjacent end of an inner tube length 30, and the latter is also preferably brazed or spot welded to the coupling at its exposed end junction therewith; i. e., at 34. Each female coupling 33 is provided with an outer threaded portion to engage an end of another outer tube unit 31, and with an inner coned seat 35 which is adapted to engage a coned nut 36 that is screwed down on the contiguous end of the corresponding inner tube length 30 and is then preferably brazed or welded thereto—as at 37. In assembling the unit sections of this dual tube structure, the adjacent ends of a pair of outer and inner pipe lengths are first screwed into the corresponding threaded portions of a male coupling 32, the outer pipe being screwed home until its extremity is jammed against the head of the coupling, as shown in Figs. 2 and 4. A female coupling 33 is next slipped over the opposite projecting end of the inner pipe length 30—the central bore of this coupling being large enough to loosely engage the unthreaded portion of the inner pipe—and screwed down onto the contiguous end of the outer pipe 31 until this end is also jammed against the shouldered head of the member 33. The coupling nut 36 is then screwed on to the unconnected extremity of the inner tube 30 until its coned surface is tightly engaged with the seat 35 of the female coupling 33. As all of the engaging parts are provided with the usual right hand threads, each successive step in the assembling operation tends to further tighten all of the joints previously made; and the final engagement of the coupling nut 36 with the coned seat 35 locks all of the assembled elements of each dual tube section into a substantially integral or unitary torque-resisting member, (against right hand rotation), since any tendency of one of these elements to rotate in a clockwise direction, with reference to the others, must result in forcing the coupled parts into an ever increasing pressure contact. The purpose of the auxiliary welded or brazed connections 34 and 37 is to lock the parts against being unscrewed by a reverse or left hand rotation, and thus produce a unit section of stem that is adapted to equally well resist either right or left hand driving torques.

The successive independent engagement of the parts 31—33, and 36—30—35 permits of a relative self adjustment of the inner and outer pipe sections, 30—31, with respect to

their end couplings, 32—33; and the final screwing down of the coupling unit 36 against its coned seat 35 not only centers the previously free end of the inner tube in the female coupling 33 (and also in the outer tube), but also imposes a longitudinal tension strain in this inner member (which acts as a tension bolt connection between the end couplings 32—33) that is transmitted through the end couplings and is balanced against a corresponding reactive compression strain in the outer tube section. These reactive balanced strains tend to further tighten the joints between the assembled elements 30—31—32—33 and thereby assist in maintaining the rigid unitary character of the double tube driving shaft sections as substantially integral torque resisting members.

Each length of finished drill stem—as thus assembled—is provided at one end with a male coupling. The thread union between the coupling elements 32 and 33 and the pipe or stem sections 31 is the same as that of the ordinary sleeve coupling for a standard single tube drill stem. Lengths of my improved double tube structure can therefore be used interchangeably with lengths of the ordinary single tube drill stem, and either form of connection can be coupled at will to the same plunger head 9.

When the coupling members 32 and 33 are screwed together the beveled end of the male coupling 32 engages with the coned extremity of the locking nut 36 in the female coupling 33, and thus seals the joints of the inner tube lengths 30 to form a continuous fluid tight conduit of uniform diameter, through which flushing liquid may be conducted to the upper end of the plunger member 2 (or 8^a). The lower end of the double tube drill stem is secured to the plunger cap 9 by means of a male coupling unit whose lower beveled end engages with the coned extremity of the collar 18; and the inner tube conduit 30 is thus put in sealed communication with the tube connections 17—12 (or 17^a—12^a) which lead to the passage-way 13 in the drill head 4.

Each of the coupling units 32 and 33 is also preferably provided with a row of apertures, 38, 38, that open into the annular chambers between the inner and outer tubes 30 and 31; and when these units are secured together, in the manner just described, the successive chambers are in free communication with each other through the apertures 38 and the spaces surrounding the locking nuts 36. The lower end of the continuous passage way, which is thus formed, opens into the annular space between the plunger cap 9 and the head 18 of the tube 17 (or 17^a); and is therefore in direct communication with the openings 24 at the top of the upper lubricant chamber. The use of only one or two of my improved double tube sections at the lower end of the drill stem will thus permit of increasing the

capacity of the reserve lubricant reservoir to any desired degree; and if the entire length of drill stem is made up of such sections the lubricating material can be supplied as necessary to the plunger reservoir (through the continuous conduit between the tubes 30 and 31) without withdrawing the tool from the bore hole, or otherwise interrupting the continuity of the drilling operations—except for 5 an occasional lifting of the drill stem for the purpose of passing fresh supplies of unguent to the lower pressure feed chamber of the device. The use of the "semi-floating" drill stem feature of my present invention makes 10 it possible, in fact, to dispense entirely with the relatively reciprocating driving sleeve and plunger elements of the hereinbefore described organizations; and to feed lubricant directly to the cutter bearings, from the surface of the ground, through the outer annular conduit in the double tube drill stem. But this functional adaptation of the last considered portion of my improved rotary drill construction is not herein specifically illustrated, as separately claimed.

The foregoing explanation of various applications of the present invention—as illustrated by two alternative forms of rotary drill construction—will make it apparent to engineers, and others familiar with the general subject to which this invention appertains, that the characteristic features of my improvements may be utilized in various types of deep well apparatus, or analogous structures, in which certain inaccessible bearing or wearing surfaces must be supplied with a suitable lubricant under considerable pressure; and it will also be obvious to such skilled workers that numerous structural changes may be made in my gravity actuated lubricating mechanism, or in my improved double tube driving stem or shaft—in order to best adapt these improvements to varying conditions of use—without altering the functional character, or the result attaining characteristics, of such structurally modified embodiments of the present invention. The only limitations which I seek to impose on the scope of this disclosure are those indicated in the accompanying claims:

1. A driving shaft or stem for deep well drills and analogous apparatus, comprising a series of tubes of substantially different diameters disposed one within the other, 55 multiple part coupling units secured to the contiguous ends of said tubes and having fluid circulating passages formed therein, said coupling units comprising means for radially and longitudinally uniting said tubes to form a substantially integral torque resisting member.

2. A double walled driving stem for deep well apparatus which comprises a series of tubes of substantially different diameter disposed one within the other, and a series of

perforated coupling units secured to threaded ends of the said tubes and adapted to radially unite said tubes into a substantially integral torque resisting member having two continuous and independent passage ways therethrough, substantially as described.

3. A driving stem for deep well rotary drills which consists of two tubular members of substantially different diameter disposed one within the other, a male coupling adapted to radially unite adjacent ends of these tubes in a tangentially rigid torque resisting member, a female coupling engaging the said male coupling, and a locking nut cooperatively engaged with the said female coupling and with the contiguous extremity 70 of one of the said tubes.

4. A driving stem for deep well rotary drills which consists of two tubes of substantially different diameters arranged one within the other, a male coupling engaging adjacent ends of the said tubes, a female coupling secured to the opposite extremity of another tube, and a beveled end lock nut secured to the contiguous extremity of another inner tube and engaged with a coned 80 socket in said female coupling.

5. A deep well apparatus which comprises a double tube driving shaft leading from the top to the bottom of the well and having two separate conduits extending therethrough, a driven head operatively connected to the lower end of the said shaft, a passage way extending through said head and in communication with one of the said shaft conduits, a lubricant reservoir in the driven member, and means for establishing communication between said reservoir and the other of said conduits in the driving shaft.

6. A rotary boring tool which comprises the combination of a drill head, a double tube drill stem slidably but non-rotatably connected thereto, a lubricant reservoir in said head and means for establishing intermittent communication between said reservoir and a longitudinal passage way in said drill stem.

7. A rotary boring tool which comprises the combination of a drill head, a plunger member slidably but non-rotatably coupled thereto, a lubricant reservoir of variable volume between the relatively movable head and plunger members, a second reservoir within the plunger, and means for establishing communication between said reservoirs when the head and plunger members are separated and the first mentioned reservoir is expanded.

8. A rotary boring tool which comprises a drill head, a drill stem member adapted to move longitudinally of the said head, means for holding the relatively movable members in non-rotatable relation, a reservoir of variable volume between the said movable parts, a spring adapted to hold said

parts in expanded position, a second reservoir of fixed volume, and means for opening communication between the variable and fixed volume reservoirs when the former is 5 expanded by the said spring.

9. In a rotary boring tool the combination of a drill head, a drill stem for rotating said head, means intermediate said head and said stem for permitting a limited longitudinal 10 movement of the two parts, a reservoir of variable volume between the relatively movable head and drill stem members, a spring mounted on said head and adapted to support a substantial part of the weight of said 15 drill stem, and means for maintaining a fluid pressure within said reservoir to nearly balance the unsupported part of said weight.

10. In a rotary boring tool the combination of a drill head for supporting the boring bits, 20 a drill stem, means for slidably but non-rotatably coupling said head to said stem, a lubricant reservoir of variable volume bounded by said relatively slidably parts, ducts leading from said reservoir to the bearings of said boring bits, and an adjustable spring closed valve controlling the passage 25 of material through said ducts.

11. In a rotary drilling tool for deep wells 30 the combination of a drill head, a drill stem assembly adapted to move longitudinally with respect to said head, means for holding these relatively movable parts in non-rotatable relation, a reservoir of variable volume between said parts, means within said reservoir for substantially balancing the weight 35 of the drill stem assembly, a second reservoir of fixed volume carried by said assembly, and means for establishing an intermittent communication between said reservoirs when 40 the tool is in operation.

12. In a rotary boring tool the combination of a drill head, a double walled drill stem slidably but non-rotatably coupled thereto, a lubricant reservoir of variable volume disposed between these relatively slid- 45 able parts, a yielding resistance member adapted to transmit a substantial part of the drill stem weight to the drill head, means for varying the restraint action of the said re- 50 sistance member on the approach movements of the said drill head and drill stem and thereby controlling the discharge of lubricant from the said reservoir, a means for introducing a fresh supply of lubricant to the 55 said reservoir when the said restraint action has exceeded a predetermined value.

13. In a rotary boring tool the combination of a drill head, a driving sleeve secured thereto, a hollow plunger longitudinally 60 movable with respect to said sleeve, means for transmitting rotary movement from the said plunger to the driving-sleeve-drill-head members, a lubricant reservoir disposed between these relatively movable parts, a spring 65 closed valve disposed in an outlet from said

reservoir, and a second valve controlling communication between said reservoir and the interior of the hollow plunger.

14. In a rotary boring tool the combination of a drill head, a double tube drill stem 70 provided with two independent passage ways therethrough, a plunger member interposed between said head and stem members and adapted to move longitudinally with respect to one of them, means for transmitting rotative movement from the drill stem to the drill head, a lubricant reservoir of variable volume between the relatively movable members, means for establishing intermittent communication between said reservoir and one of the said passage ways in the drill stem, an aperture in the drill head, and a hollow member leading from said aperture to a bearing in said plunger and adapted to afford continuous communication between said aperture and the other of said drill stem passage ways. 75

15. The hereinbefore described mode of feeding lubricant to the bearings of deep well drills which consists in confining a mass of unguent in immediate proximity to said bearings, subjecting said mass to a part of the weight of the drill stem, intermittently relieving said mass from such gravity pressure, and automatically replenishing the supply of 80 confined material from a reserve volume of lubricant during such intervals of reduced pressure. 85

16. The hereinbefore described method of operating deep well drills and analogous apparatus which consists in confining a mass of lubricant in immediate proximity to the drill head, subjecting this mass of lubricant to a part of the weight of the drill stem to thereby force it to the bearings of the drill 90 head cutters, transferring a remaining part of this weight to the said cutters to thereby maintain them in proper working engagement with the bottom of the bore hole, intermittently relieving the drill stem pressure on the lubricant without removing such pressure from the drill head, and replenishing the supply of confined unguent during the 95 intervals of reduced pressure thereon. 100

17. The herein described method of feeding lubricant to the bearings of a rotary boring drill, which consists in confining a mass of unguent within said drill adjacent said bearings, subjecting said mass to the pressure of said drill stem, controlling the flow of unguent from said mass to the bearings of the drill so as to maintain said mass under a determined fluid pressure less than the pressure corresponding to the force applied by said drill stem, and intermittently relieving said mass of the weight of said drill stem 110 while replenishing the supply of unguent. 115

18. In combination in a stem for deep well drills and the like, a coupling comprising a part provided with means for securing inner 120 125 outer 130

and outer tube sections in fixed radial relation, and with a clamping surface, a part removably secured thereto and provided with means for engaging an outer tube section, 5 and with a clamping surface, inner and outer tube sections secured to said first-mentioned part, an outer tube section secured to said last-mentioned part, an inner tube section, surrounded by said last mentioned section, 10 and extending through said last mentioned part, a nut secured to said last mentioned inner tube section and engaged by said clamping surfaces on said parts.

19. A stem for deep well drills or the like, 15 consisting of two tubes of substantially different diameters arranged one within the other, a two-part coupling, one part engaging adjacent ends of said tubes, the other part secured to the opposed extremity of another 20 tube, and a conical lock nut secured to the extremity of another tube and co-operatively engaged by surfaces formed on both parts of said coupling.

20. In a rotary boring tool, the combination 25 of a drill head, a drill stem slidably but non-rotatably connected thereto, a member secured to said stem and forming, with a cavity in said head, a lubricant chamber, lubricant delivery ducts formed in said head and 30 adjustable means between said chamber and said duct for controlling the delivery of lubricant from said chamber to said ducts and for maintaining a weight-supporting fluid pressure within said chamber.

35 21. In a rotary boring tool, the combination of a drill head member, a stem member telescoping therewith and movable longitudinally thereof, resilient means enclosed within both of said members and tending to 40 move them apart, means for limiting the longitudinal movement and for holding said members against relative rotary movement and means for adjusting the initial tension of 45 said resilient means.

45 22. In combination in a deep well drilling tool, a drilling head, a drill stem member engaging said head and movable longitudinally thereof and cooperating therewith to enclose a lubricant chamber having a port leading 50 to inaccessible bearings, a valve controlling said port and means controlling said valve responsive to the pressure within said chamber.

55 23. A rotary boring tool which includes the combination of a drill head, a double tube drill stem slidably but non-rotatably connected thereto, a lubricant reservoir in said head, a longitudinal passageway in said drill stem, and an adjustable bellows valve for 60 establishing intermittent connection between said reservoir and said passageway.

65 24. A rotary boring tool which includes the combination of a drill head, a double tube drill stem slidably but non-rotatably connected thereto, a lubricant reservoir in said

head and a longitudinal passageway in said drill stem, a valve for establishing intermittent connection between said reservoir and said passageway, and means for introducing air into said passageway so that said valve 70 will be given pressure adjustment.

In testimony whereof I have hereunto set my hand.

FRANK L. O. WADSWORTH.
